UNITED STATES PATENT OFFICE

WALLACE W. SHAW, OF CHICAGO, ILLINOIS

SECTIONAL ASH CONTAINER

Application filed April 26, 1928. Serial No. 273,056.

My invention relates to improvements in concrete structures and has special reference to improvements in box-like structures such as boxes or containers suitable for ash containers.

The object of the invention is to provide a concrete structure of suitable size, form and construction, whereby each of the parts of the box can readily be produced in one place and 10 readily transported to the place of use and there readily assembled to form the box and including means for permanently joining the several parts and thus completing the box.

A valuable feature of my invention resides 15 in the novel means which I provide for permanently locking the walls at the corners of the box and for protecting the metallic means which I use for this purpose.

Other features of importance will be made 20 clear in the following description taken in conjunction with the accompanying drawings forming part of this specification, and in which:—

Fig. 1 is a perspective view of a concrete 25 structure in the form of an ash box and illustrating one application of my invention;

Fig. 2 is a fragmentary vertical section of the lower part of the box on the line 2—2 of Fig. 1;

Fig. 3 is a fragmentary vertical section of 30 the box on the line 3—3 of Fig. 1;

Fig. 4 is a fragmentary horizontal section on the line 4—4 of Fig. 2;

Fig. 5 is a fragmentary end elevation of one 35 of the side walls of the box;

Fig. 6 is an enlarged fragmentary horizontal section on the line 6—6 of Fig. 1; and

Fig. 7 is a fragmentary vertical section on the line 7—7 of Fig. 6.

40 The structure which I have selected as typical of my invention, is an ash box or container, suitable for placement upon the rear end of a house lot to hold the ashes from the furnace and to permit them to be readily removed therefrom.

The box or container as shown is of rectangular form and is made in sections, each section constituting one wall of the box.

45 The box shown is made up of six sections, 50 the bottom 1, the top 2, the front 3, and three

similar side walls 4. Each of these sections is suitably reinforced by means of coarse woven wire or other suitable reinforcements 5 formed to lie substantially at the middle of the thickness of the section. 55

The sections are each substantially square and each is formed for its particular place, except the three walls 4 which are all identical and are interchangeable with each other as to position. 60

The bottom 1 is generally flat but has a raised outer edge 6 within which the bottom edges 7 of the side walls are placed. The inner side of this raised edge is inclined outwardly to permit the ready placement of the side walls thereon. At one side, the bottom 1 is provided with a horizontal projection 8 extending nearly across the front of the box for convenience in shoveling the ashes out of the box. At the outer end of this projection 70 it is inclined upwardly as shown at 9 to a height substantially equal to the height of the raised edges 6 on the other sides of the floor to prevent liquid dripping out of the box. 65

The front 3 is provided at its lower end 75 with a wide opening 10 above the floor projection 8 through which the contents can be shoveled out. The front is also provided with forward extensions 11 which form sides leading back from the opening and formed to provide inclined edges 12 extending up from the outer end of the floor extension 8 to the front wall 2 at the top of the opening 10. These inclined edges form an inclined surface upon which a closure plate or door 13 rests at its 80 edges. Just above the opening 10, the front wall is formed outwardly, as shown at 14 and formed hinge members 14' are embedded in this outer edge of the projecting part 14. This

formation is for the purpose of spacing the hinge members 14' out from the front member 3 so that when the door 13 is swung up to open position, as shown in dotted lines in Fig. 1, it will rest back against the front in stable condition until again purposely swung down. 85

The side portions of the door 13 close upon the inclined edges of the extensions 11 and against the forward edge of the bottom extension 8 and the door is heavy enough to rest against these supporting edges and prevent 90

95

The side portions of the door 13 close upon the inclined edges of the extensions 11 and against the forward edge of the bottom extension 8 and the door is heavy enough to rest against these supporting edges and prevent 95

Posterior view of the skull of *Thylamys macrurus* (M. 1000) showing the large, well developed, and slightly divergent canines.

Posterior view

cesses adapted to be filled after the connectors are in place.

3. In a box-like structure of the kind described, preformed sections constituting a base, walls and a top, the walls provided with cut away inner corners at their ends, metal anchor members embedded in the walls and having loop-like portions extending into said cut away corners, metal connections arranged in the corners of the box engaging said anchors and locking the walls together, and the anchors and connections being arranged within the thickness of the walls, the spaces at the corners of the box being adapted to be filled with concrete after the walls are set up and locked together and whereby the connecting members are embedded in concrete.

4. In a box-like structure of the kind described, preformed sections comprising a base, a top and side walls, an upstanding ledge around the outer edge of the base, the lower edges of the side walls formed to receive said ledge, and the top formed with an overhanging rim on its lower side adapted to encircle the upper edges of the side walls, and means for locking the side walls together at their adjacent ends.

5. In a box-like structure of the kind described, preformed sections constituting a base, a top and side walls, all adapted to be assembled to form a box, one side wall formed with an exit opening in its lower end, the top formed with an inlet opening at one side, the top being adapted to be set on the box with its inlet opening in any position relatively to the exit opening, which may be desired.

6. In a structure of the kind described, preformed sections constituting a base, a top and four side walls, one of the walls provided with an opening at its lower end, the wall above the opening projecting outwardly, a door member for closing said opening hinged to said projecting part of the wall, the upper edge of the door member located beneath said projecting part when closed, as and for the purpose specified.

7. In a box-like structure of the kind described, a door opening in one side of the box, a door member for closing said opening, the upper edge of the door member when in closed position being located beneath the upper side of the door opening so that water running down the outside of the box above said opening will be prevented from entering the box.

8. In a structure made up of prepared sections including walls, the walls having vertical opposed grooves at the inner edges of their ends, metallic connection members embedded in the walls and having loop-like parts projecting out into said grooves, staples adapted to be driven straddling opposed connections, the legs of the staples guided by the walls of said grooves as the staples are driven.

9. A box-like structure comprising a bot-

tom, a top and four side walls, each made of reinforced concrete, the walls having grooves at the inner sides of their ends, metallic connection members embedded in the walls and presenting loop-like parts in said grooves, staples straddling opposed connections and binding the walls together, and said grooves filled with concrete or the like and whereby the staples and connecting loops are embedded.

10. In a box-like structure comprising a bottom, a top and four side walls each made of reinforced concrete, one wall having an opening extending up from its lower end, the bottom having a horizontal extension at one side adapted to co-operate with the said opening in the side wall for providing an exit opening, inclined side walls extending out from said side wall at each side of said opening, the lower end of said opening giving free access to the front corners of the box, and means for retaining the several parts of the box in assembled relation.

11. A box-like structure of the kind described made up of preformed sections constituting a bottom, side walls and a top, the side walls having cooperating fillable spaces at their contacting ends, means adapted and arranged to lie within said fillable spaces and secure the walls together, as and for the purpose specified.

In witness that I claim the foregoing as my invention, I affix my signature this 21st day of April, 1928.
